DESIGN FOR A COMB

Robert Lester Motley, Dayton, Ohio, assignor of fifty per cent to John W. Dickerson, Newark, N. J.

Application September 2, 1944, Serial No. 115,172

Term of patent 14 years

(Cl. D86—8)

To all whom it may concern:

Be it known that I, Robert L. Motley, a citizen of the United States, residing at Dayton, in the county of Montgomery and State of Ohio, have invented a new, original, and ornamental Design or a Comb, of which the following is a specification, reference being had to the accompanying drawing, forming part thereof.

Figure 1 is a front elevational view of a comb showing my new design, and

Figure 2 is an edge elevational view thereof,
and

Figure 3 is a top plan view thereof.

I claim:

The ornamental design for a comb, as shown.

ROBERT LESTER MOTLEY.
